UNITED STATES PATENT OFFICE

2,635,532

CONTAINER IMPRINTER

James Stewart, Homewood, Ill.

Application April 28, 1949, Serial No. 90,111

15 Claims. (Cl. 101—40)

1

This invention relates in general to the art of imprinting on containers, and more particularly to a machine and method for imprinting on containers having a generally cylindrical shape.

While the invention in its broader aspects may be utilized for imprinting any desired indicia on such containers, the present machine and method has been designed primarily for imprinting a color designation on containers carrying paints, enamels, lacquers and the like to indicate the color therein, and illustrates a modified form of machine from that disclosed and claimed in my copending application filed April 28, 1949, Serial No. 90,112.

It has been the practice in the past in the paint industry to place around the containers, such as the gallon, half-gallon and quart sizes, a paper label which had printed thereon all of the necessary information including the color designation. When this was done, the containers were made up in the customary way and a great number of printed labels could be stored in a relatively small amount of space, and thereafter placed around the container when ready for use. A great number of labels could be made up in advance bearing all of the various color designations so that these labels would be available for use at a later date. The matter of storage for these labels presented no problem.

The advent of the lithographing method of printing labels directly on metal containers before the container was formed, thereupon presented such storage problems when the color designation of the contents was imprinted on the containers at the same time. The labels on all of the containers, regardless of the color of the paint or enamel within the container, are substantially alike. It is necessary, however, that each container bear thereon indicia for the purpose of informing the ultimate purchaser as to the color of the paint or enamel therein. It was found that if the color designation were to be imprinted on the container at the same time the label was printed thereon, a tremendous inventory would have to be maintained because of the storage space required for the empty containers.

It was then decided that if some effective way could be arrived at for later applying the color designation, if it were omitted at the time the label was printed directly on the container, the inventory could be considerably reduced, thus obviating the necessity for a large storage space.

The problem may be better understood when it is recognized that there is customarily a pre-

5 determined location on the container at which the color designation appears. Due to the fact that the label is multicolored and carries a design as well as certain printed matter, the color designation must be placed thereon at a location suitable therefor and which must be determined in advance.

10 It is, therefore, the principal object of the present invention to provide a machine for imprinting indicia on a container at a predetermined location thereon.

15 Another object of the invention is to provide a machine adapted to automatically print indicia on a substantially cylindrical container at a predetermined location thereon.

20 A further object of the invention is to provide a machine wherein a novel form of positioning means is actuated for positioning a predetermined point on the container, whereby suitable indicia may thereafter be imprinted at a predetermined location on the container.

25 Still another object of the invention is to provide a machine for imprinting indicia on containers wherein a positioning station and a printing station are located.

30 A still further object of the invention is to provide in a container imprinting machine a positioning station and a printing station together with means at the positioning station to automatically position a container with respect to the printing station, whereby the container may thereafter be conveyed to the printing station and have indicia printed on the container at a predetermined location thereon.

35 Still another and more specific object of the invention is to provide a container imprinting machine having a positioning station and a printing station, wherein means are provided which are actuated in response to certain means on the container to position a point on the container with respect to the printing station, whereby the container may thereafter be conveyed to the printing station and have indicia printed thereon at a predetermined location.

40 A further object of the invention is to provide a container imprinting machine having a positioning station and a printing station, wherein means at the positioning station will cause the container to rotate until a certain point on the container reaches a predetermined position with respect to the printing station, whereupon the container may be conveyed to the printing station and have indicia imprinted thereon at a predetermined location.

45 Still another object of the invention is to pro-

vide a container imprinting machine having a positioning station and a printing station therein and wherein rotary means at the positioning station will rotate the container on the spot until a point on the container reaches a predetermined position with respect to the printing station. After the point on the container reaches this predetermined position, suitable means are provided which are actuated in response to the point on the container which will stop rotation thereof, whereupon the container may be conveyed to the printing station and have indicia imprinted on the container at a predetermined location thereon.

A still further object of the invention is to provide a method of imprinting indicia on a substantially cylindrical container, whereby the indicia will appear at a predetermined location on the container.

Other objects and advantages of the invention will become apparent upon reading the following description taken in conjunction with the accompanying drawings in which:

Fig. 1 is a side elevational view of the machine embodying the invention;

Fig. 2 is a top plan view of the machine shown in Fig. 1;

Fig. 3 is a horizontal sectional view taken along line 3—3 of Fig. 1;

Fig. 4 is an enlarged vertical sectional view taken along the line 4—4 of Fig. 2;

Fig. 5 is a fragmentary enlarged plan view of the reciprocating carriage which advances the containers intermittently through the machine;

Fig. 6 is an enlarged fragmentary vertical sectional view taken along the line 6—6 of Fig. 4;

Fig. 7 is a fragmentary enlarged side elevational view of the carriage for advancing the containers intermittently and shown in its forward position;

Fig. 8 is a side elevational view of the carriage similar to Fig. 7, but showing the carriage just before it reaches the opposite end of its travel;

Fig. 9 is an end elevational view of the carriage as viewed from the right hand end in Fig. 8;

Fig. 10 is an enlarged fragmentary sectional plan view similar to Fig. 3 but showing the printing mechanism in printing position and showing certain other parts in detail;

Fig. 11 is a fragmentary vertical sectional view taken along the line 11—11 of Fig. 3;

Fig. 17 is a plan view of the container of Fig. 16 showing the depression in the container in section;

Fig. 18 is a fragmentary view of a container similar to Fig. 17, but showing the actuating means as a projection on the container;

Fig. 19 illustrates a still further modification of actuating means for the positioning mechanism;

Fig. 20 is a plan view of the container shown in Fig. 19 with a portion thereof shown in section;

Fig. 21 illustrates a still further modified form

of actuating means for the positioning mechanism;

Fig. 22 is a wiring diagram showing the sequence and manner of operating the reciprocating carriage; and

Fig. 23 is a wiring diagram showing the electrical circuit for actuating the printing mechanism and the reciprocating member which rolls the container over the type at the printing station.

In accordance with the present invention, it is contemplated that cylindrical containers, either filled or empty, be fed into the machine at one end thereof in an upright or vertical position, and then conveyed to a positioning station. Means are employed at the positioning station to rotate the container so that it will assume a position with respect to the printing station such that, when the container is conveyed from the positioning station and rolled to and past the printing station, the correct location on the container will present itself to the printing mechanism, whereby the indicia will be imprinted on the container at the pre-selected location.

It is important that the printing on the container take place so that the indicia appear at the desired location thereon. In order to assure this, it is necessary to properly position the container before it reaches the printing mechanism. As the containers are fed into the machine, the relative position of the containers will vary considerably, and various means have been provided to properly position the containers for printing thereon.

Any suitable means may be provided to be actuated in response to something on the surface of the container itself to carry out the positioning step. In the preferred form of the invention illustrated herein, a deformation in the container cooperates with switch means to act as the positioning means to stop rotation of the container at the proper time. In determining the proper position of the container, it will depend upon the circumference of the container and the distance between the positioning and printing stations. The location on the container where the printing is to take place is first determined, and then the container is positioned in such manner at the positioning station so that, when the container rolls along its circumference and over the type at the printing station, this predetermined location where the printing is to take place will properly present itself to the printing mechanism.

The containers are fed into the machine at one end thereof in an upright position. To prevent jamming of the containers at the entrance to the machine, suitable means have been provided to admit the containers thereto one at a time. Each container as it enters the machine is initially placed in the first position and then conveyed to the positioning station where it is rotated to a predetermined position and then held in that position. The predetermined position to which the container is rotated is determined by the location on the container where the printing is to be applied. When the proper position of the container is reached at the positioning station, it is then conveyed to a point immediately adjacent the printing station, whereupon suitable mechanism is provided to roll the container over the type on the printing mechanism for impression purposes. The conveyor mechanism which moves the containers intermittently through the machine then conveys the printed container to

another conveyor which carries it away from the machine.

The particular means on the container which is illustrated as being the preferred embodiment of the invention herein contemplates a deformation in the container at a predetermined point thereon. This deformation actuates a switch energizing an electrical circuit, actuating a pneumatic system and applying brakes to immediately stop further rotation of the container. Such a deformation may consist of an indentation or a projection. Another method which may be employed contemplates the use of an electrical circuit wherein the container itself is grounded, and when a roller arm is caused to contact a bare part of the container such as the weld seam, the electrical circuit is completed to actuate the pneumatic means and brakes to stop rotation. A still further method involves the use of photosensitive means, all of which will be described more fully hereinafter.

The printing mechanism which is located at the printing station preferably consists of a miniature type of printing press having a type form therein, a pair of inking rollers and an inking disc. After each impression the entire mechanism is retracted to cause the rollers to roll over the inking disc and over the type to apply additional ink thereto. This operation must take place in timed relation with the movement of the containers from the positioning station to the printing station. Any suitable means may be used to actuate the printing mechanism at the proper time, but the particular means disclosed herein for accomplishing this purpose includes switch means actuated by the movement of the roller device which causes a container to roll over the type. When this device reaches its extreme position in one direction, the switch is actuated to retract the printing mechanism.

Referring now more particularly to the drawings, and especially to Figs. 1, 2 and 3, the machine may include any suitable supporting framework consisting, for example of the upright columns 1 adapted to support a shelf 2 near their lower ends, which shelf may have mounted thereon much of the electrical and pneumatic apparatus for carrying the machine through its cycle. A second shelf 3 is supported at the upper ends of the main columns 1 and additional supporting columns 4 extend upwardly therefrom to support the main shelf 5.

A track or runway is provided on the shelf 5 in which the containers are adapted to be moved intermittently from the entrance of the machine to the exit thereof. This track or passageway is formed by spaced angle members 6 and 7, each of which comprises a horizontal portion 8 and a vertical portion 9. The horizontal portions 8 are secured directly to the shelf 5 and the vertical portions 9 are parallel and form the sides of the passageway through which the containers 10 are moved.

A reciprocating carriage arrangement is provided for intermittently advancing the containers through the machine one at a time. This carriage has a sliding movement along the elongated spaced guide rods 11 and 12 located below the shelf 5 and supported at opposite ends in the bearing blocks 13 and 14 (see Figs. 4 and 5). The carriage includes the spaced side bars 15, each of which has secured thereto a plurality of bearing blocks slidable along one of the guide rods. These bearing blocks at each end of the side bars 15 are indicated by the numeral 16, and the in-

termediate bearing blocks are indicated at 17. These side bars 15 extend along the outside of the guide rods 11 and 12 and are suitably fastened together at one end thereof to form a rigid carriage adapted to reciprocate longitudinally along the guide rods.

An elongated link 18 is positioned at each side of the carriage inwardly of the bearing blocks 16 and 17, and each link 18 has pivotally mounted thereon a plurality of fingers or dogs 19, 20 and 21. Each of the fingers 19 is pivotally mounted to its adjacent and corresponding link 18 by a pivot pin 22. The fingers 20 are similarly pivoted to the links 18 by means of pivot pins 23, and the fingers 21 are likewise pivotally mounted by means of the pins 24 to the same links. Each finger is also pivoted at its lower end to its adjacent bearing block by means of elongated pins 25.

The forward end of the carriage adjacent the outlet end of the machine has a plate 26 connected between the forward ends of the links 18 (Figs. 5 and 9). An angle member 27 is secured to the underside of the plate 26 so that one leg thereof extends downwardly and may have a plate 28 secured thereto. This plate 28 has a portion extending outwardly therefrom at one side of the machine and has a dual function as will be more fully described hereinafter. A pair of spaced plates 29 are secured to the forward side of the angle member 27, such as by welding or the like, so that one end of a piston rod 30 may be received between the plates. A pivot pin 31 extends between the plates 29 and through the end of the piston rod 30, whereupon reciprocation of the entire carriage results when the piston rod 30 is caused to move upon the actuation of a piston within the cylinder 32.

It will be noted that the connecting arrangement between the piston rod 30 and the reciprocating carriage is made at one end of the carriage directly to the links 18 so that a forward or rearward movement of the rod is transmitted directly to these links. It will be evident from viewing Fig. 4 that a movement of the piston rod 30 toward the left will move the links 18 and the fingers connected therewith toward the left to lower the upper ends of the fingers below the shelf 5 during the return movement of the carriage. These fingers are thus enabled to move below the containers previously positioned on the shelf 5. When the carriage reaches its extreme left hand position and the piston rod 30 is caused to move toward the right, it will exert a pull on the links 18 causing the fingers to pivot about the pins 25 in a clockwise direction, thereby to elevate the fingers above the shelf 5 to contact the lower ends of the containers.

If there is a container in the first position it will be contacted by the fingers 19 and moved to the second position which is the positioning station. A container at the positioning station will be picked up by the fingers 20 and carried to the printing station. The container at the printing station will then be caused to roll over the type in the printing mechanism, but this movement is slightly faster than the movement of the fingers so that after the printing has taken place, the fingers 21 will thereupon pick up the container in the final position and carry it to the outgoing conveyor.

The positioning mechanism

When a container reaches the positioning station it is caused to rotate until the location on the container where the printing is to take place

reaches a predetermined position relative to the printing station. In the preferred embodiment of the invention illustrated herein, this position is determined by a deformation in the container which may be either an indentation or a projection. This deformation is contacted by a switch which energizes an electrical circuit and actuates a pneumatic system and applies brakes to immediately stop rotation of the container.

The means for rotating the container include a supporting bracket 33 mounted on the shelf 3. This bracket has a base member 34, a vertical portion 35, and an upper horizontal bearing portion 36. A cup shaped supporting member 37 is mounted at the top of the horizontal bearing 36 and has a recess therein to receive a disc 38. This disc preferably has the upper surface thereof knurled or otherwise roughened to carry the container with it in its rotary movement when it is elevated to bear against the bottom of the container. The disc 38 is secured to the supporting member 37 which, in turn, is fastened to the vertical shaft 39 (Figs. 4 and 6). A sprocket wheel 40 is mounted on the vertical shaft 39 and has a sprocket chain 41 engaged therewith. A thrust bearing 42 is spaced upwardly on the shaft 39 from the sprocket wheel 40 and bears upwardly against a bearing 42a. The bearing 42a has a press fit within an opening in the upper horizontal bearing 36. A coiled compression spring 43 surrounds the shaft 39 and bears upwardly at its upper end against the thrust bearing 42 and downwardly at its lower end against the sprocket wheel 40. This spring 43 normally urges the vertical shaft 39 in a downward direction.

A bearing 44 is mounted on the lower leg 34 of the supporting bracket 33 and receives the lower end of the shaft 39. The bottom of shaft 39 abuts against the upper end of a piston rod 45 which is caused to reciprocate vertically by means of air applied to one side of a piston within the cylinder 46. In the operation of this mechanism an electrical switch is momentarily closed to actuate an air valve (not shown) and elevate the piston rod 45. The elevation of piston rod 45 also elevates the shaft 39 and the members 37 and 38 so that the roughened surface of the member 38 will contact the lower end of a container at the positioning station, thereupon elevating the container from the shelf and causing rotation of the container when shaft 39 is rotated.

The sprocket chain 41 also engages a sprocket wheel 47 (Fig. 3) mounted for rotation about a shaft 48 supported between the spaced horizontal arms 49 and 50 of a bracket member 51. This bracket member 51 is bolted to the shelf 3 through its base 52. A plate 53 extends between and below the bearing blocks 16 at the left hand end of the carriage and has a finger 54 depending downwardly therefrom in engagement with the sprocket chain 41. It will therefore be clear that any reciprocation of the carriage which advances the containers intermittently will also move the sprocket chain 41 in a reciprocating movement to rotate the shaft 39 by reason of its connection with the sprocket wheel 40.

It will be evident that a container is caused to rotate only when the shaft 39 is in its elevated position. This is controlled by the electrical and pneumatic systems so that the shaft 39 is elevated only on the return movement of the carriage toward the left, at which time the fingers 19, 20 and 21 are below the surface of the shelf 5 and thereby perform no function.

When the shaft 39 is elevated, it moves a sufficient distance to clamp the container between the member 38 at the bottom thereof and a disc 55 at the top thereof which has a pad 56 at its underside. This pad may be formed preferably of rubber or other resilient material so that rotation of the member 38 will cause a rotation of the container by reason of the clamping action with the rotatable disc 55.

The disc 55 has a hub portion at the upper side thereof adapted to receive a bearing member 57 within which one end of a screw threaded shaft 58 is located. The shaft 58 threadedly engages a boss 59 on a horizontally extending bar 60 (Figs. 1, 2 and 4). This bar 60 extends longitudinally of the machine above the containers as they move through the machine and has a cross member 61 welded or otherwise secured thereto which extends transversely of the machine. The cross member 61 is bolted or otherwise secured to the upper side of bars 62 supported on the upper ends of the supporting columns 63. There are four of these columns 63 extending upwardly from the main shelf 5 and form the supports for the bars 60 and 61 in which the disc 55 is mounted at the lower end of the adjustable shaft 58.

Another bar 64 is suspended below the bar 60 and extends from one side of the positioning station to the printing station. A similar and shorter bar 65 is also suspended below the bar 60 but at the opposite side of the positioning station. The bar 64 is adjustably suspended by means of the vertical rods 66 and 67 slidably mounted in blocks 68 and 69. The short bar 65 is likewise adjustably mounted on a rod 70 passing through a similar block 71. Screws 72 threadedly engage the blocks 68, 69 and 71 and are adapted to hold the respective rods in any position to which adjusted.

The upper disc 55 may be adjusted by rotating the shaft 58 by means of the adjusting member 73 secured thereto. These adjustments are utilized primarily for different size containers passing through the machine. For example, the machine as illustrated may be set for gallon containers, but when quart containers are to be printed, the disc 55 and the bars 64 and 65 will have to be lowered to accommodate the height of the smaller container. The bars 64 and 65 act primarily as an upper guide for the upper ends of the containers as they pass through the machine.

The main shelf 5 is provided with a rectangular elongated opening 74 through which the fingers 19, 20 and 21 are adapted to pass in order to project above the surface of the shelf and convey the containers in their intermittent movement from station to station.

When the container is caused to rotate and the location on the container where the printing is to take place is properly positioned with respect to the printing station, two operations take place immediately to stop further rotation of the container. One operation is the application of brakes at opposite sides of the container. The other operation is the lowering of the vertical shaft 39 to move the rotating member 38 out of contact with the bottom of the container.

In describing these operations and the actuation of the various parts, reference will now be made more particularly to Figs. 1, 2, 3 and 10. A supporting member 75 projects outwardly from one side of the vertical leg 9 of the angle member 6 and supports a plate 76 for pivotal movement 75 by means of a pivot pin 77. A microswitch 78 is

mounted on the upper side of the plate 76 and has a switch arm 79 projecting therefrom. The outer end of the switch arm 79 is provided with a roller 80 adapted to contact the surface of the container and to be caused to move the switch arm 79 either inwardly or outwardly when contacted by the deformation. This movement of the arm closes the electrical circuit to the brakes and simultaneously causes a lowering of the vertical shaft 39. A small disc 81 is pivotally mounted as at 82 to the underside of the plate 76. This disc 81 is substantially triangular in shape and is provided with rollers 83 and 84 at the two innermost corners thereof as clearly shown in Fig. 10. Two other rollers 85 and 86 are also mounted on the plate 76 in alignment at an angle with respect to the rollers 83 and 84. A coiled tension spring 87 is secured at one end to a pin 88 extending below the plate 76 and at its other end to an adjustable finger 89. The finger 89 threadedly engages a bracket 90 (Fig. 1) secured to one of the supporting columns 63 and may be adjusted by means of the thumb screws 91 to regulate the tension of the spring 87.

The plate 76 has a downwardly extending arm 92 at one side thereof and terminates in a threaded opening to receive the adjustable stop screw 93. The spring 87 tends normally to urge the plate 76 in a clockwise direction, as viewed in Fig. 10, about its pivot point 77 and will urge the plate in this direction until the screw 93 comes against the vertical leg 9 of the angle member 6. This will be the position of the plate 76 together with the parts mounted thereon when there is no container at the positioning station. As a container 10 is moved toward the positioning station by the fingers 19, the surface of the container will first come against the rollers 85 and 86 to urge the plate 76 and its connected parts about the pivotal point 77 in a counterclockwise direction. As the container continues its movement to the positioning station, it will then come against the roller 83 and when it is properly positioned immediately above the rotating member 38 both of the rollers 83 and 84 will bear against the surface of the container. This is important because the containers are not always perfectly round and it is imperative that the switch arm 79 be not actuated by any deformity in the container other than the one particularly designed for the purpose of actuating the switch arm. If the container is slightly out of round, the rollers 83 and 84 will prevent the switch arm 79 from actuating the switch until the proper time.

The form of the invention illustrated herein utilizes a deformation in the surface of the container such as the depression 94 for actuating the switch arm 79. The deformation may be either a depression as shown at 94 or a projection as shown at 94a in Fig. 18. When the depression is used, the roller 80 will fall into the depression to move the switch arm 79 outwardly to close the switch 78. If a projection such as 94a is used, then the roller 80 will cause the switch arm 79 to be moved in the opposite direction to close the microswitch 78. In either event an electrical circuit is energized to cause the application of the brakes and the lowering of the rotating device.

The braking mechanism is more clearly shown in Fig. 3 and consists of the solenoids 95 and 96 mounted on opposite sides of the passageway 70 through which the containers are moved, and are preferably mounted on the angle guide members 6 and 7. Each of the solenoids 95 and 96 is provided with an arm or plunger 97, the outer end of which is pivotally connected to an arm 98 by 75

means of the pivot pin 99. The outer end of each arm 98 is suitably connected to one arm of a bell crank lever 100 pivotally mounted at 101. The other arm of the bell crank lever 100 is pivotally mounted at 102 to a bracket 103 connected to a brake shoe 104. The other end of each bell crank lever 100 has a coiled tension spring 105 connected thereto by means of the pin 106. The other end of each spring 105 is fastened to a plate 107 secured to one of the supporting columns 63. The spring 105 tends normally to urge the brake shoe associated therewith in a direction away from the container in the positioning station. The spring also urges the associated bell crank lever 100 against a suitably positioned stop member 108.

When the deformation 94 or 94a in the container reaches the position of the switch arm 79 as the container is being rotated, the switch arm 79 will close the switch 78 immediately energizing an electrical circuit to actuate the solenoids 95 and 96 to apply the brakes 104 at diametrically opposed locations on the container. At the same time an electrical circuit will be energized to actuate the air valve in the pneumatic cylinder 46 to reverse the direction of air pressure against the piston therein and lower the rotating member 38 out of contact with the bottom of the container. These two operations will insure that the container will stop rotating when the deformation in the container reaches the switch arm 79. It is understood, of course, that the deformation in the container is placed in a predetermined location with respect to the place on the container where the printing is to take place, so that when the container is moved to the printing station this predetermined location on the container will be positioned properly when the container is rolled over the type on the printing mechanism.

Additional means are provided for preventing any overrunning of the container as it is moved into the positioning station. The containers when filled are quite heavy and may not stop at the positioning station in an exact concentric location with respect to the rotating member 38. For this reason additional stop means are provided as shown more clearly in Figs. 7 and 8 for the purpose of preventing the container from moving past its proper position. This mechanism includes a horizontally disposed lever arm 109 suitably mounted on the cross member 53 below the bearing blocks 16 at one end of the reciprocating carriage. The stop member includes a finger or dog 110 adapted to extend above the shelf 5 and be moved in the path of the incoming container. The member 110 has a leg 111 extending downwardly therefrom and is pivoted at 112 to a support 113 mounted on the upper horizontal portion 36 of the supporting bracket 33. The pivot point 112 is so located on the stop member that the weight of the leg 111 will normally pivot the member out of the path of a container. When the leg 111 is in this downward position as shown in Fig. 8, and the reciprocating carriage moves forwardly to position the next successive container in the positioning station, the container which has just been positioned will be moved to the printing station. The stop member 110 is allowed to remain in its lowered position until after the first container has cleared this member. At this moment the end of lever arm 109 will come against the leg 111 to elevate the dog above the shelf 5 and into the path of the incoming container. This dog is so positioned that it will properly locate the container concentrically with respect to the rotating mechanism. The support 113 is provided with an

upper limit pin 114 to limit the upward movement of the member 110 and with a lower limit pin 115 to limit the movement of the stop member in the opposite direction.

The printing mechanism

The printing mechanism holding the type against which the containers are rolled for printing the color designation or other indicia thereon is preferably in the form of a miniature printing press, the details of which will be more clearly understood by reference to Figs. 2, 3, and 11.

The mechanism comprises a base member 116 mounted on a plate 116a secured to the main shelf 5. The mechanism is provided with a type bed 117 and a small inking disc 118. The type bed 117 is adapted to hold type 119 therein and to be moved into position to contact the outer surface of the container as it is rolled past. Rollers 120 journaled at each end in a bearing member 121 mounted on the side arms 122 are adapted to roll over the inking disc to gather ink during the printing operation and to deliver this ink to the type after each impression. The side arms 122 extend downwardly and rearwardly and are secured to a horizontally disposed rotatable shaft 123 mounted in bearings 124 on the base of the mechanism. The mechanism is mounted for sliding movement between the sides of the base 116.

The printing mechanism is caused to retract or move rearwardly away from the container passageway at the end of each printing operation, and during this retraction the rollers 120 are caused to move downwardly over the type 119 for re-inking. This movement of the rollers is imparted thereto by means of an arm 125 secured at its lower end to the shaft 123. The upper end of arm 125 has a roller 126 extending outwardly at one side thereof between flanges 127 on a supporting bracket 128. This bracket 128 has a flange 129 at its lower end whereby it may be rigidly secured to the plate 116a. It will be noted in Fig. 11 that the full line position of the printing mechanism illustrates the mechanism when it is retracted. As the mechanism is caused to move forward toward the next container to be printed, the stationary bracket 128 will cause rotation of arm 125 in a counter-clockwise direction. The shaft 123 to which arm 125 is connected will also rotate. Rotation of shaft 123 in this direction will carry the side arms 122 upwardly and cause the rollers to assume a position on the inking disc 118.

A bracket, having a horizontal portion 130 and a vertical bifurcated portion 131, is mounted on the base of the press and is movable therewith in its reciprocating movement. The space between the bifurcations 131 is adapted to receive an annular groove in an internally threaded adjusting member 132. This adjusting member threadedly engages the outermost threaded end of a piston rod 133 connected to a piston (not shown) movable within the air cylinder 134.

As soon as the printing on a container has been accomplished, a microswitch energizes an electrical circuit which actuates an air valve (not shown) at one end of the air cylinder 134 to retract the piston rod 133 and the printing mechanism connected thereto, whereupon the type is re-inked as above explained. When the printing mechanism is retracted to its full extent it closes another microswitch to energize an electrical circuit which actuates the air valve reversing the pressure within the cylinder 134, thereby causing

the printing mechanism to again assume its printing position for the next container.

The microswitch which causes the return of the mechanism to printing position is indicated by the numeral 135 and is provided with a switch arm 136 extending outwardly into the path of a finger 137 on the adjusting member 132. When the mechanism reaches its full retracted position the finger 137 will contact the arm 136 to close switch 135 and energize the electrical circuit which actuates the air valve and returns the mechanism to printing position.

The adjusting member 132 is utilized for the purpose of regulating the pressure of the type on the container. This may be done by rotating the member 132 to adjust the mechanism with respect to the piston rod 133. The finger 137 is adapted to be located in a plurality of different positions at the rear of the adjusting member 132 so that it may be always in line with the switch arm 136. The details of this construction are not shown herein inasmuch as it is a conventional design.

It will thus be clear that the normal position of the printing mechanism is the forward position shown in Fig. 10. After each impression, the mechanism is caused to retract and re-ink the type and again move into printing position before the next succeeding container is brought into printing position. The retraction of the printing mechanism is caused by the energization of an electrical circuit hereinafter to be described but which circuit is energized by the closing of a switch caused by movement of the feeding arm 35 which rolls the container over the type.

Container rolling mechanism

The manner in which each container is fed into the machine to its first position, then conveyed to the positioning station, and thereafter to the printing station, has been explained above as being an intermittent movement of the container through the machine. After the container is properly positioned at the positioning station, it is then conveyed by the fingers on the reciprocating carriage toward the printing station where it is caused to roll over the type in the printing mechanism. The container rolling mechanism which causes the container to roll over the type is more clearly illustrated in Figs. 1, 2, 3, 10, 11 and 12.

An angle plate having a vertical leg 138 is provided with a yieldable friction member 139, such as rubber, on its inner face. An opening 140 is provided in the vertical leg 9 of the angle 6 to permit the friction face or pad 139 to contact and roll a container over the type in the printing mechanism. The bottom horizontal leg 141 of the angle member is caused to ride along the surface of the horizontal portion 8 of the angle member 6 in its reciprocating movement for rolling a container over the type and then returning to pick up the next container.

One end of the horizontal portion 141 has an upstanding bifurcated part 142 adapted to receive the annular groove 143 of an adjusting nut 144. This adjusting nut threadedly engages one end of a piston rod 145 which has at its other end a piston 146 mounted for reciprocation within an air cylinder 147. The air cylinder 147 is supported at one end by means of a bracket 148. This bracket also supports one end of a guide rod 149 which guides the container roller device in its reciprocating movement. The other end of the guide rod 149 is mounted in a bearing 150. A sleeve 151 is mounted for sliding movement

along the guide rod 149 and is provided along one side thereof with upper and lower spaced radially extending flanges 152. A pair of links 153 and 154 have one end thereof received between the flanges 152 and are mounted for pivotal movement by means of the pivot pins 155 and 156. The other end of link 153 is received within the spaced sides of a lug 157 and is mounted for pivotal movement therein by means of the pin 158. The opposite end of link 154 is likewise received between the spaced sides of a lug 159 and is mounted for pivotal movement therein by means of the pivot pin 160. These lugs 157 and 159 are secured to the vertical leg 138 of the main angle member, whereupon reciprocating movement of the angle by means of the piston rod 145 will cause the friction face of the pad 139 to move either toward or away from a container. The horizontal portion 141 of the angle member is provided with a pair of stop members 161 and 162 to limit the inward and outward movement of the angle member carrying the friction face 139.

The normal position of this container rolling device is at the extreme left hand end of the guide rod 149 as viewed in Fig. 3. As the piston rod 145 moves inwardly, or toward the right, the first movement will be to move the angle member carrying the friction face 139 until the link 153 abuts against the stop member 162. At this point the friction face 139 will bear against the adjacent container with sufficient pressure to cause it to roll over the type in the printing mechanism. The rolling of the container will be in a counter-clockwise direction as viewed in Fig. 10 although bodily movement of the container will be toward the right or exit end of the machine. When the piston rod 145 reaches the end of its inward stroke the printing will have been completed and the piston rod will be caused to move on its return stroke toward the left. The initial movement in this direction will cause the friction face 139 and the angle member on which it is mounted to move toward the left until the link 153 abuts against the stop member 161. During this slight movement the sleeve 151 will not be moved and therefore the friction face 139 will be moved outwardly away from the container passageway. This will insure that the friction face will not contact any container until it is again caused to move in the opposite direction. When the piston rod 145 reaches its full outward stroke and begins its return stroke the friction face will again be moved inwardly to contact the container and roll it past the type in the printing mechanism.

The sleeve 151 is provided with an angle member 163 at one end thereof having an opening therein adapted to receive a limit screw 164. This limit screw 164 is adapted to contact a switch arm 165 of a microswitch 166 which energizes an electrical circuit to actuate an air valve (not shown) in the cylinder 141, thereupon reversing the direction of movement of the piston rod 145.

The air valve in cylinder 141 is actuated to cause inward movement of the piston rod 145 by a container contacting the switch arm 165 of a microswitch 168 as it is moved through the container passage toward the printing station. Closing of switch 168 will energize an electrical circuit to actuate the air valve in cylinder 141 and cause inward movement of the piston rod 145. It will be clear when the electrical diagrams are considered that the retraction of the printing mechanism is caused by the closure of switch 166 so that the printing mechanism is operated to re-

ink the type in timed relation with movement of the containers through the machine.

The intake conveyor

5 The containers are fed into the machine one at a time, and in order to prevent jamming of the containers at the inlet end of the machine, suitable mechanism has been provided on the intake conveyor to prevent such jamming by permitting 10 the containers to enter the machine singly. Reference will now be made particularly to Figs. 13 and 14 wherein the intake conveyor is generally indicated by the numeral 169. This conveyor slopes downwardly toward the inlet end of the machine and is provided with a pair of spaced guide bars 170 and 171. The containers enter the conveyor in an upright position and rest on rollers 172 which are rotatably mounted at each 15 end thereof in the spaced channel members 173 and 174. At one side of the machine the channel member 173 supports a plate 175 on which is rockably mounted an E-shaped member 176. This member 176 is mounted for a limited rocking movement about the pivot member 177.

20 One leg 178 of the E-shaped member has a roller 179 mounted on the outer end thereof which normally extends into the path of an incoming container. The roller 179 is mounted between the spaced sides of a support 180 which has a rod 181 thereon mounted for sliding movement within a bearing member 182. A coiled compression spring 183 surrounds the rod 181 and normally urges the support 180 and roller 179 in an outward direction, but will permit a limited movement inwardly thereof when forced in that direction by a container on the conveyor. A bumper post 184 is mounted on the plate 175 for the purpose of limiting the rocking movement of the E-shaped member in a clockwise direction as viewed 25 in Fig. 14.

20 The other leg 185 of the E-shaped member 176 is provided with a roller 186 at its outer end. Another bumper post 187 is mounted on the plate 175 against which one end of the E-shaped member 176 may abut in order to limit the rocking movement of this member in a counter-clockwise direction as viewed in Fig. 14.

30 A coiled tension spring 188 is secured at one end to a post 189 on the plate 175 and at its other end to a pin 190 adjacent the outer end of the center leg of the E-shaped member. It will be noted that the pin 190 and post 189 are in direct alignment with the center of the pivot member 177 so that the spring 188 will hold the E-shaped member against either bumper post 35 when caused to rock in one direction or the other.

30 Normally the E-shaped member 176 is against one or the other of the bumper posts 184 or 187. 60 When a container enters the conveyor at the inlet end, the member 176 will be against the bumper post 187, whereupon the roller 179 will be moved into the path of such container. Suitable mechanism is provided to rock the E-shaped member 176 about its pivot point at the proper time to move it against the bumper post 184. 65 This movement will thereupon permit the container to move downwardly along the conveyor until it strikes against the roller 186. When the operating mechanism is actuated to rock the E-shaped member 176 in a counter-clockwise direction against the bumper post 187, the container will then be free to continue along the conveyor and to enter the machine at the first position. 70 This device acts to prevent jamming of the con-

tainers at the inlet end of the machine and to permit the containers to enter the machine one at a time.

The actuating mechanism which causes the E-shaped member 176 to rock includes an arm or crank member 191 extending outwardly at one side of the pivot member 177. The outer end of this arm 191 receives a rod 192 which is connected at its opposite end to a member 193 by means of a universal joint connection 194. The member 193 has an adjustable connection 195 to another connecting member 196 at the opposite end thereof which, in turn, is connected to a member 197 by means of a universal joint 193. The member 197 is secured to one end of an elongated rod 199 mounted for longitudinal sliding movement in the supports 200 extending upwardly from the shelf 3.

The opposite end of rod 199 is provided with spaced collars 201 and 202, both of which are secured directly to the rod.

Referring again for the moment to Fig. 9, it has been previously explained that the plate 28 is secured to the reciprocating carriage which carries the fingers for moving the containers in an intermittent movement through the machine. This plate 28 extends outwardly from one side of the carriage and is provided with a slot 203 extending upwardly from the lower edge thereof to accommodate the rod 199. The plate 28 is located between the two collars 201 and 202 which are spaced apart the proper distance to be contacted by the plate 28 and move the rod 199 for a short distance at each end of the movement of the reciprocating carriage.

Thus, just before the carriage reaches its extreme forward position of conveying the containers toward the outlet end of the machine, the plate 28 will contact the collar 202. Further movement of the carriage to the end of its reciprocating movement will carry with it the collar 202 and rod 199. The direction of movement of the rod 199 will be toward the right as viewed in Fig. 13 and will thereupon cause the pivot means 177 to rotate in a clockwise direction as viewed in Fig. 14. This will move the E-shaped member 176 against the bumper post 184 to interpose the roller 186 into the path of the next succeeding container. The spring 188 will hold the member 176 in this position.

During the return movement of the carriage to its initial position, the plate 28 will ride freely along the rod 199 until just before it reaches its final position as illustrated in Fig. 8, whereupon the plate 28 will contact the collar 201. Further movement of the carriage toward its initial position will thereupon cause the rod 199 and its connected parts to move toward the left, as viewed in Fig. 13, to thereupon impart a counter-clockwise rotation of the E-shaped member 176 until it comes against the bumper post 187. This movement of member 176 will remove the roller 186 from the path of the container, thus permitting the container to move downwardly along the conveyor to the first position in the machine. At this point the roller 179 will have been moved into the path of the next container to prevent that container from entering the machine until after the previous container has been moved out of the first position.

As may be seen in Figs. 7, 8 and 9, an elongated rod 204 may be welded or otherwise suitably secured to the bottom edge of plate 28. This rod 204 is adapted to contact the roller 205 of a switch arm 206 on the microswitch 207. The location 75

of this switch 207 with respect to the other parts of the machine may be more clearly understood by reference to Fig. 1 where it is the center switch of the three mounted on shelf 3.

Switch 207 is caused to open on the forward stroke of the reciprocating carriage as it feeds the containers through the machine. The rod 204 is mounted on plate 28 which is secured to the links 18 by means of the angle member 27. 10 It has been explained above how the links 18 have a downward movement while the reciprocating carriage moves back to its original position toward the intake end of the machine. It was also explained that the links 18 move upwardly when 15 the containers are being conveyed through the machine. This up and down movement of links 18 will therefore be imparted to the rod 204 so that it will be elevated and out of contact with the roller 205 on the switch arm 206 when the 20 carriage is feeding containers through the machine. On the return stroke of the carriage to initial feeding position the rod 204 will be lowered to close the contacts of switch 207. The 25 operation of switch 207 in the complete circuit will be more clearly understood during the description of the electrical circuit. For the present, however, it is sufficient to note that the switch 207 will be open during movement of the 30 carriage toward the outlet end of the machine and thus will prevent the energization of the electrical circuit which applies the brakes and which elevates the rotating mechanism to rotate the container at the positioning station. This 35 switch acts as an additional safety feature to prevent operation of the brakes and rotary means at any time except on the return stroke of the carriage to initial position.

Referring for the moment to Fig. 1, it will be seen that the system is provided with two limit 40 switches 208 and 209 which govern the reciprocating movements of the carriage. Microswitch 208 has a switch arm 210 with a roller 211 at the outer end thereof. Microswitch 209 has a switch arm 212 provided with a roller 213 at its outer end. Both of these switches normally close and normally open contacts and will be closed or opened depending upon the position of the switch arm. The arm of each switch will remain in either of its two positions for opening or closing the contacts. A finger 214 is mounted on the underside of one of the bearing blocks 16 and is adapted to contact the roller 211 of the switch arm 210 on the switch 208 on a return movement of the reciprocating carriage to its initial 45 position. Closing of switch 208 will actuate the air valve in air cylinder 32 to draw the reciprocating carriage toward the outlet end of the machine and advance the containers to their next position.

When the carriage reaches its extreme position toward the outlet end of the machine, finger 214 will operate switch arm 212 to close switch 209 thereby actuating an air valve in air cylinder 32 for moving the reciprocating carriage back toward the inlet end of the machine.

It will be clear that without some means for de-energizing the circuit, the carriage would reciprocate constantly whether or not there were any containers in the machine. To overcome this difficulty the machine is provided with a time delay relay which is actuated by a microswitch 215 mounted on a plate 216 on the channel 174 of the conveyor 169 (Fig. 14). This microswitch 215 has an arm 215a with a roller 217 on the outer end thereof adapted to be contacted by an

incoming container. As will be seen when the wiring diagrams are considered, the time delay relay will be operated upon the closing of switch 215 by movement of the switch arm 215a inwardly. The timing may be such that when the last container is released by movement of roller 186 out of the path thereof, this container will enter the machine and will be positioned and printed and finally delivered at the outlet end of the machine before the electrical circuit will be de-energized by the time delay relay.

While switch 215 and the time delay relay to which it is connected is not necessary to the successful operation of the machine, it is, nevertheless, a desirable feature to cause the automatic stopping of the machine after the last container has been printed.

The electrical circuits

For purposes of illustration and for ease in understanding the sequence of operation of the various mechanical parts described above, the electrical circuit for the machine has been divided into two wiring diagrams, Figs. 22 and 23. On the actual machine these are two separate circuits. Fig. 22 illustrates the electrical circuit for the microswitch 215 which operates the time delay relay as shown in Fig. 14; the switches 208 and 209 which reverse the direction of movement of the conveyor carriage; the switch 207 which permits switch 78 to energize the circuit to the brakes and the rotating member for rotating the container. Fig. 23 is the wiring diagram which includes only the reversing switch 166 operating the roller arm 138 on the piston rod 145; the main actuating switch 168; and the reversing switch 135 on the printing mechanism.

Referring now to Fig. 22, the operation will be explained beginning with the position of the parts when the piston rod 30 is retracted into air cylinder 32 at the end of the delivery stroke of the conveyor carriage. As previously stated, switch 208 has a normally closed contact. In this position the blade of switch 208 will be in the normally closed position as shown in Fig. 22 in full lines. The finger 214 on the carriage will be against the arm 212 of switch 209 to move the blade against the normally open contact as shown in dotted lines in Fig. 22. It will also be assumed that a container is in the conveyor closing switch 215 to operate the time delay relay.

The main power line has a transformer therein so that the circuit operates on about 8 volts. With the position of the various parts as just described, current will then pass from one side of the line through the branches 218, 219 and 220 to the lines 221 and 222. The current then flows through the now closed but normally open contact of switch 209 through the time delay relay 223 and line 224 to the air valve in cylinder 32 which is designated as the "out" position in the diagram. The current then passes back to the other side of the line through branch 225. Current also passes from the time delay relay 223 through line 224a to the "up" air valve in cylinder 46 to elevate the shaft 39 and clamp the container for its rotary movement. This will immediately force the piston rod 30 and the conveyor carriage connected thereto outwardly and rearwardly to move the conveyor back to its original starting position. At this time the fingers 19, 20 and 21 will be in lowered position.

With the fingers and their connecting links 18 lowered, the rod 204 will come against the arm 206 of microswitch 207 to close the switch and

energize the switch 78 at the positioning station. At this point, then, current will flow through branches 218, 219 and 220 through the normally closed contact of switch 208 and thence through the branch 226 to the closed contacts of switch 207. This switch is connected directly to switch 78 at the positioning station through line 227 so that when switch 78 is closed by movement of the switch arm 79 due to the deformation in the container, the remainder of the circuit will be energized as will be presently pointed out.

Simultaneously, current will flow through switch 207 and through the branches 228 and 229 to the No. 4 contact of the relay generally indicated at 229a. This relay has four sets of contacts, three of which are normally open and one of which is normally closed. When the deformation in the container actuates switch arm 79 to close switch 78, the circuit will then be completed through the lines 230 and 231 to the relay solenoid coil 232. The circuit is then completed through branch 225 to the other side of the line, thereupon energizing the solenoid 232 which is mechanically connected to the switch arms of the relay to close the contacts Nos. 2, 3 and 4 and to open the contact No. 1.

Switch 78 is closed only momentarily; but its closing energizes the relay solenoid 232 whereupon the circuit through the now closed contact No. 4 of the relay will act as a holding circuit to hold the relay in actuated position.

Actuation of switch 78 indicates that the container is now properly positioned and should be stopped in this position without further rotation. At this moment current passing through the holding circuit including branch 229 and the No. 4 contact of the relay will also be carried through branch 233 to the now closed No. 2 contact of the relay and through the branches 234 and 235 to the "down" air valve of cylinder 46. This immediately lowers the rotating member 38 and vertical shaft 39 out of contact with the container to stop further rotation thereof. The circuit is completed through line 236 back to branch 225 to the other side of the transformer.

At this moment the brakes are also applied and the brake circuit is connected directly across the main power supply. The brake solenoids 95 and 96, only one of which is illustrated in the wiring diagram, are energized upon the closing of the No. 3 contact in the relay 229a. Current then passes from one side of the main power line through branches 237 and 238 to the now closed No. 3 contact in the relay and then through the branches 239 and 240 to the brake solenoid. The solenoids are then energized by current passing back to the other side of the line through branch 241. At this point in the operation the container has stopped rotating and has been positioned properly with respect to the printing station so that when it is conveyed to the printing station and is rolled over the type in the printing mechanism, the printing will be located at the proper predetermined location on the container.

The piston rod 30 continues to move outwardly and to move the conveyor carriage back to its original starting position with the fingers down. When the carriage reaches the end of its stroke back to its original position, the finger 214 on the end of the carriage will come against the switch arm 210 of switch 208 and will close the normally open contacts as indicated in dotted lines in Fig. 22. This closing of the normally open contact is momentary and will thereupon feed current through line 242 to the "in" side of the air cylinder

32. The air valve will then be actuated to retract the piston rod 30 and begin movement of the carriage toward the outlet end of the machine thereby advancing the containers in the machine to the next successive positions thereof. This momentary closing of the normally open contact of switch 208 will open the normally closed contact of the switch thereby breaking the holding circuit through the No. 4 contact of the relay 229a. thereby opening Nos. 2, 3 and 4 contacts and closing No. 1 contact. At this same moment when the normally open contact of switch 208 is closed, current will be fed through branches 243 and 244 through the now closed No. 1 contact of the relay and through branches 245, 234, and 235 to the "down" side of cylinder 46 to insure that rotating disc 38 is below the shelf 5 and out of the way of the incoming container.

During this movement of the conveyor carriage toward the outlet end of the machine, the fingers 19, 20 and 21 will be raised and the rod 204 will be moved upwardly out of contact with the switch arm 206 on switch 207. Switch 207 will thereupon be opened to the dotted line position shown in Fig. 22 and no current will be fed to the actuating switch 78. Therefore, even if the switch 78 is closed for any reason, neither the brakes nor the rotating disc can be moved into the path of an incoming container during the entire travel of the conveyor carriage and containers toward the outlet end of the machine. When the conveyor carriage reaches the end of its movement toward the outlet end of the machine, finger 214 will thereupon close the normally open contact of switch 209 and the above described sequence of operations will be repeated. This movement will take place as long as there are any containers in the incoming conveyor for actuating switch 215 to operate the time delay relay 223. This time delay relay may be set to automatically prevent further operation of the machine after the last container has been delivered to the outlet end of the machine.

Referring now to Fig. 23, this circuit is a separate one for operating the piston rod 145 to actuate the container roller device and for reciprocating the printing mechanism to ink the type thereon after each printing operation. In this case a transformer is also placed in the main power line. Normally, all three switches 135, 166 and 168 are open. As a container is moved from the positioning station toward the printing station, it will come against the arm 167 of switch 168 to close the circuit through the air valve which moves the piston rod 145 inwardly. This is merely a momentary closing of switch 168 to actuate the air valve. At this moment current passes from the transformer through lines 246 and 247, through the air valve in the cylinder 147, and through the "in" side to operate the valve. The current then continues to the switch 168 through branches 248, 249 and 250. The current is then fed back to the other side of the line through the branches 251, 252, 253, 254 and 255.

The type on the printing mechanism will be in printing position, and retraction of piston rod 145 will bring the friction face 139 of the roller arm in forceful contact with the adjacent container. Continued retraction of piston rod 145 will cause a rolling movement of the container against the type in the printing mechanism as previously explained above.

When piston rod 145 reaches the end of its inward stroke after the printing on the container

has taken place, the adjustable screw 164 will come against the arm 165 to close the contacts of switch 166. At this moment current from one side of the transformer passing through valves 5 in the cylinder 147 will then be fed through the "out" valve and through branch 256 through the closed contacts of switch 166 and thence back to the other side of the transformer through branches 253, 254 and 255. This completes the circuit through the air cylinder 147 to actuate the air valve therein and immediately begin movement of the piston rod 145 outwardly and back toward its original position where it may pick up the next container for printing.

15 At this same moment the circuit will be completed through the air cylinder 134 to retract the piston rod 133 for re-inking the type. This circuit becomes energized by reason of the closing of the contacts in switch 166 and may be traced as follows. Current from the transformer is fed through line 257 to the "in" side or valve of air cylinder 134. The current is then carried back to the other side of the transformer through branches 258, 259, 260 and 261, through the closed contacts of switch 166, and then through the branches 253, 254 and 255.

20 Here again the closing of switch 166 is momentary and merely acts to operate the air valves in the air cylinders 147 and 134 to move the piston rod 145 outwardly and the piston rod 133 inwardly. When the piston rod 133 reaches the limit of its inward stroke a finger on the mechanism closes the contacts of switch 135, whereupon current will be fed from one side of the 25 transformer through the "out" side of the air cylinder 134 and through lines 262, 263 and 264 back to branches 254 and 255 to the other side of the transformer. The closing of switch 135 is also momentary because as soon as the air 30 valve is actuated by movement of the piston rod 133 inwardly, the printing mechanism will then be moved outwardly back to printing position whereupon the contacts of switch 135 will be opened. The next container being moved into 35 printing position will again close the contacts of switch 135 and the above operation will be repeated for each container.

The modified forms of the invention

40 Throughout the above description the proper positioning of the container relative to the printing station has been determined by a deformation in the container. It was explained that this deformation could be either a depression or a projection to operate a switch arm to close the contacts of a switch energizing an electrical circuit to stop further rotation of the container. In my above referred to copending application a grounding circuit as well as the use of photo-sensitive means were described as being equally applicable as a substitute for the deformation in the container for accomplishing the same result. These same forms of the invention may be applied as well in the present machine. For purposes of comparison and ease in understanding 45 these modifications they have been illustrated in Figs. 16 to 21 inclusive with a greatly simplified wiring diagram.

50 Figs. 16 and 17 refer to the depression in the container as more completely illustrated and described in the preferred embodiment of the invention herein. Either the depression 94 or the projection 94a could be utilized to actuate the roller 80 on the switch arm 79 to close the 55 contacts of switch 73. In this simplified wiring

diagram current will pass from one side of the main power line through line 265 through a coil 266 and line 267. When switch 78 is closed the circuit is completed through lines 268 and 269 to the other side of the main power line 270. Energizing the coil 266 will mechanically close the switch 271 completing a circuit from one side of the line 265 through branches 272 and 273 through the solenoid 274 and back to the other side of the line through branch 275. The solenoid 274 may be considered as representative for the purpose of actuating the brakes against the rotating container and the air valve which lowers the rotating disc 38.

Figs. 19 and 20 illustrate a different type of circuit where the bottom of the container is grounded and a roller 276 completes an electrical circuit when it bears against a bare part on the metal container. Where containers have a lithographed label applied thereto, this label does not customarily cover the weld seam so that the roller 276 may be positioned to contact the seam 277 of the container at the moment when the location on the container where the printing is to take place is properly positioned relative to the printing station. In this case the circuit will be completed from one side 278 of the line through branch 279 to the coil 280. The lines 281 and 282 connect the other side of coil 280 with the roller 276. When contact is made with the weld seam or other bare spot on the container, the circuit will then be completed through ground to the other side 283 of the main power line. This, then, energizes the coil 280 to close the contacts of switch 284, whereupon current flows from line 278 through the contacts and branch 285 to energize solenoid 286. The other side of the solenoid is connected through line 287 to the other side 283 of the main power line. Here again the solenoid 286 may be considered as the actuating mechanism for the brakes and the lowering of the rotating disc 38 to immediately stop rotation of the container in the proper position for printing at the moment roller 276 comes into contact with the bare part 277 on the container.

Fig. 21 illustrates the use of a photoelectric cell which energizes an electrical circuit when activated either by light increase or light decrease. In the preferred embodiment of this form of the invention, the photosensitive means is caused to be activated upon light decrease. This guards against activation of the cell when there are no containers in the machine. As more fully explained in my copending application, the lithographed labels on the container are usually colored with a border of a different color. As an example, it was stated that the label may be primarily yellow with a border of blue, although these colors are not intended in any way to be limiting. The light source 288 is directed against the surface of the container and is so arranged as to reflect a part of the light to be received by the eye of the photoelectric cell 289. There is a greater amount of reflectivity from yellow than blue so that when one of the border lines of the label passes the cell 289, there will be a light decrease, whereupon the cell will be activated to energize an electrical circuit to operate the brakes and lower the rotating disc. It must be borne in mind that the location on the container where the printing is to take place must be properly positioned with respect to the printing station so that when the container is conveyed to the

printing station and rolled over the type, the indicia or color designation will be properly located thereon. The photosensitive means will be so positioned in the machine as to stop rotation of the container when it is thus properly positioned.

As an additional assurance that the container will be stopped in its proper position, a switch 290 having a switch arm 291 may be positioned at one side of the machine to be contacted and closed by the container only after it is completely positioned on the rotating disc. The switch 290 must be closed before the circuit can be energized, thus if a border line such as the blue line 292 is positioned immediately in front of the cell 289 as the container moves into the positioning station, the circuit would be immediately energized without any rotation having taken place. The use of switch 290 will prevent this occurrence because the circuit cannot be completed, even though the cell is activated, until the switch 290 is closed. One side of the switch 290 is connected through line 293 to the cell and the other contact of switch 290 is connected by line 294 to a relay mechanism 295. The details of this relay mechanism are not disclosed herein since it is an ordinary commercially available relay device. Another line 296 is connected from the cell 289 to the other contact in the relay 295. Power is supplied from the main power lines 297 and 298 to the relay 295. When switch 290 is closed and the border line 292 of the label on the container is seen by the eye of the photoelectric cell 289, this light decrease will activate the cell to close the circuit and actuate the relay 295. This actuation of the relay will then cause current to pass from one side of the line 297 through line 299 through the solenoid 300 and back to the other side of the line through the branch 301. Here again the solenoid 300 is considered as being operable to actuate the brakes as well as the lowering of the rotating disc 38, both of which cooperate to immediately stop rotation of the container.

From the foregoing description it will be evident that a novel form of mechanism has been provided which is completely automatic in its operation for the purpose of feeding cylindrical containers one at a time into a machine where the container is first positioned and then printed upon at a predetermined location on the container. Various means have been specifically disclosed herein for carrying out the various operations. The preferred embodiment of the invention contemplates the use of a deformation in the container for actuating a switch to stop rotation of the container in a predetermined location with respect to the printing station. This same result may be accomplished by other means such as the grounding system or the use of a photoelectric cell as above described. The machine is capable of handling containers of different sizes by means of various adjustments. If the containers are smaller in diameter than those illustrated herein, means may be provided to move the angle members 6 and 7 toward each other for narrowing the passageway through which the containers pass. If the containers are shorter than those shown herein, then the bars 64 and 65 as well as the rotating disc 55 may all be lowered to accommodate the shorter containers. The time delay relay device, while not necessary is, nevertheless, useful to automatically stop operation of the machine after printing of the last container and thus pre-

vents continued operation of the machine and continued reciprocation of the conveyor carriage when there are no containers in the machine.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

The invention is hereby claimed as follows:

1. A machine for imprinting indicia at a predetermined location on a cylindrical container, including a positioning station and a printing station, rotating means at said positioning station for frictionally engaging the container, means for rotating said friction means to rotate the container to a predetermined position relative to said printing station, braking means adapted to contact the container to prevent overrunning thereof past said predetermined position, reciprocating carriage means for conveying the container after proper positioning from said positioning station to said printing station, printing means at said printing station to imprint indicia at a predetermined location of the container determined by the position of the container at the positioning station, reciprocating friction means movable in one direction in a path to cause frictional engagement of the friction means with said container to roll the container past said printing means, and means to displace said friction means out of said path when moved in the opposite direction to avoid contact with a container.

2. A machine for imprinting indicia at a predetermined location in a cylindrical container, including a positioning station and a printing station, rotatable means at said positioning station for frictionally engaging the ends of a cylindrical container, means for rotating said rotatable means to rotate the container to a predetermined position relative to said printing station, braking means adapted to contact the container to prevent overrunning thereof past said predetermined position, reciprocating carriage means for conveying the container after proper positioning from said positioning station to said printing station, printing means at said printing station to imprint indicia at a predetermined location on the container determined by the position thereof at the positioning station, reciprocating friction means movable in one direction in a path to cause frictional engagement of the friction means with said container to roll the container past said printing means, and means to displace said friction means out of said path when moved in the opposite direction to avoid contact with a container.

3. A machine for imprinting indicia at a predetermined location on a cylindrical container, including a positioning station and a printing station, means for conveying a container in an upright position to said positioning station, means at said positioning station for rotating a container about its vertical axis to a predetermined position relative to said printing station, braking means adapted to contact the container to prevent overrunning thereof past said predetermined position, reciprocating carriage means for conveying the container after proper positioning from said positioning station to said printing station, printing means at said printing station to imprint indicia at a predetermined location on the container determined by the po-

sition thereof at the positioning station, reciprocating friction means movable in one direction in a path to cause frictional engagement of the friction means with said container to roll the container past said printing means, and means to displace said friction means out of said path when moved in the opposite direction to avoid contact with a container.

4. A machine for imprinting indicia at a predetermined location on a cylindrical container, including a positioning station and a printing station, means for conveying a container in an upright position to said positioning station, rotatable means at said positioning station adapted to frictionally engage an end of the container, means for rotating said rotatable means when in frictional contact with the container to rotate the container to a predetermined position relative to said printing station, braking means adapted to contact the container to prevent overrunning thereof past said predetermined position, reciprocating carriage means for conveying the container after proper positioning from said positioning station to said printing station, printing means at said printing station to imprint indicia at a predetermined location on the container determined by the position thereof at the positioning station, reciprocating friction means movable in one direction in a path to cause frictional engagement of the friction means with said container to roll the container past said printing means, and means to displace said friction means out of said path when moved in the opposite direction to avoid contact with a container.

5. A machine for imprinting indicia at a predetermined location on a cylindrical container, including a positioning station and a printing station, means for conveying a container in an upright position to said positioning station, rotatable means located below the container at the positioning station adapted to move upwardly to frictionally engage the bottom of the container, means for elevating said rotatable means against the bottom of the container, means for rotating said rotatable means to rotate the container to a predetermined position relative to said printing station, means for lowering said rotatable means after the container has reached said predetermined position thereby to stop further rotation thereof, braking means adapted to contact the container to prevent overrunning thereof past said predetermined position, means for conveying the container after proper positioning from said positioning station to said printing station, printing means at said printing station to imprint indicia at a predetermined location on the container determined by the position thereof at the positioning station and reciprocating friction means adapted to frictionally engage the container to roll the container past said printing means.

6. A machine for imprinting indicia at a predetermined location on a cylindrical container, including a positioning station and a printing station, rotatable means at said positioning station for frictionally engaging a container, means for rotating said rotatable means to rotate the container to a predetermined position relative to said printing station, reciprocating carriage means for conveying the container after proper positioning toward said printing station, a longitudinally reciprocating member having friction means thereon adapted to contact one side of the container for rolling the container past

said printing station, means for reciprocating said member between retracted and advanced positions, means for moving said member to retracted position in a path different from the path travelled thereby in moving to advanced position to avoid contact with a container, and means at said printing station to imprint indicia at a predetermined location on the container determined by the position of the container at the positioning station.

7. A machine for imprinting indicia at a predetermined location on a cylindrical container, including a positioning station and a printing station, rotatable means at said positioning station for frictionally engaging the ends of a cylindrical container, means for rotating said rotatable means, means responsive to indexing means on the container to stop rotation of the container when the indexing means thereon reaches a predetermined position relative to said printing station, reciprocating carriage means for conveying the container after proper positioning from said positioning station to said printing station, longitudinally reciprocating friction means adapted to frictionally engage the surface of the container when moved in one direction for rolling the container past said printing station, means for moving said friction means out of contact with the container on the return movement thereof, and means at said printing station to imprint indicia at a predetermined location on the container determined by the position of the indexing means at the positioning station.

8. A machine for imprinting indicia at a predetermined location on a cylindrical container, including a positioning station and a printing station, conveyor means for feeding containers in an upright position into the machine, means on said conveyor means for feeding the containers into the machine one at a time, reciprocating conveyor means for moving the containers successively through the machine in an intermittent movement, means at said positioning station for rotating the container to a predetermined position relative to said printing station, said reciprocating conveyor means adapted to convey the properly positioned container from said positioning station to said printing station, means at said printing station to imprint indicia at a predetermined location on the container determined by the position thereof at the positioning station, and means on said reciprocating conveyor means to control the operation of said means for feeding the containers into the machine one at a time.

9. A machine for imprinting indicia at a predetermined location on a cylindrical container, including a positioning station and a printing station, rotatable means at said positioning station for frictionally engaging the container, means for rotating said rotatable means to rotate the container to a predetermined position relative to said printing station, an electrical circuit, means including said rotatable means and a braking means operable upon energization of said electrical circuit to stop rotation of the container in said predetermined position, means operable in response to indexing means on the container to energize said electrical circuit and stop rotation of the container, reciprocating carriage means for conveying the container after proper positioning from said positioning station to said printing station, printing means at said printing station to imprint indicia at a predetermined location on the container determined by the position of the container at the positioning station.

tion of the indexing means at the positioning station, reciprocating friction means movable in one direction in a path to cause frictional engagement of the friction means with said container to roll the container past said printing means, and means to displace said friction means out of said path when moved in the opposite direction to avoid contact with a container.

10. A machine for imprinting indicia at a predetermined location on a cylindrical container, including a positioning station and a printing station, rotatable means at said positioning station for frictionally engaging the container, means for rotating said rotatable means to rotate the container to a predetermined position relative to said printing station, an electrical circuit, means including said rotatable means and a braking means operable upon energization of said electrical circuit to stop rotation of the container, reciprocating conveyor means including pivotally mounted fingers adapted to engage an end of the container when moving in one direction and to pivot out of engagement when moving in the opposite direction, means for reciprocating said conveyor means for moving the container from said positioning station to said printing station when said conveyor is moved in one direction, other switch means in said electrical circuit adapted to be closed by movement of said conveyor in the opposite direction thereby to prevent energization of said circuit at any time except during movement of the conveyor in said opposite direction, and means at said printing station to imprint indicia at a predetermined location on the container determined by the position of the indexing means thereon at the positioning station.

11. A machine for imprinting indicia at a predetermined location on a cylindrical container, including a positioning station and a printing station, rotatable means at said positioning station for frictionally engaging a container, means for rotating said rotatable means to rotate the container to a predetermined position relative to said printing station, means for conveying the container after proper positioning toward said printing station, reciprocating friction means adapted to contact the container when moved in one direction and roll the container past said printing station, printing mechanism at said printing station having type thereon adapted to remain stationary in printing position to bear against the container as it is rolled past the printing station to imprint indicia at a predetermined location on the container determined by the position of the container at the positioning station, means to move said friction means out of the container-contacting path when moved in the opposite direction, and means operable in timed relation with the movement of said last named friction means in the opposite direction to re-ink the type on said printing mechanism after each printing operation.

12. A machine for imprinting indicia at a predetermined location on a cylindrical container, including a positioning station and a printing station, rotatable means at said positioning station for frictionally engaging a container, means for rotating said rotatable means to rotate the container to a predetermined position relative to said printing station, means for conveying the container after proper positioning from said positioning station to said printing station, printing means at said printing station to imprint indicia at a predetermined location on the container determined by the position of the container at the positioning station.

container after proper positioning toward said printing station, a reciprocating friction member having friction means thereon adapted to contact the container for rolling the container past said printing station, means for reciprocating said member, reciprocating printing mechanism at said printing station having type thereon adapted to be moved into contact with the container as it is rolled past the printing station to imprint indicia at a predetermined location on the container determined by the position of the container at the positioning station, an electrical circuit, means operable upon energization of said electrical circuit to move said printing mechanism out of contact with the container and to re-ink the type in said printing mechanism, and switch means operable in response to movement of said reciprocating friction member to energize said electrical circuit and re-ink said type.

13. A machine for imprinting indicia at a predetermined location on a cylindrical container, including a positioning station and a printing station, rotatable means at said positioning station for frictionally engaging the container, means for rotating said rotatable means to rotate the container to a predetermined position relative to said printing station, an electrical circuit, means including a braking mechanism adapted to grip the container at opposed points thereon and operable upon energization of said electrical circuit to stop rotation of the container in said predetermined position, means operable in response to a deformation on the container to energize said electrical circuit and stop rotation of the container, means for conveying the container after proper positioning from said positioning station to said printing station, printing means at said printing station to imprint indicia at a predetermined location on the container determined by the position of the deformation at the positioning station, and reciprocating friction means adapted to frictionally engage the container to roll the container past said printing means.

14. A machine for imprinting indicia at a predetermined location on a cylindrical container, including a positioning station and a printing station, rotatable means at said positioning station for frictionally engaging the container, means for rotating said rotatable means to rotate the container to a predetermined position relative to said printing station, an electrical circuit, means including a braking mechanism adapted to grip the container at opposed points thereon and operable upon energization of said electrical circuit to stop rotation of the container in said predetermined position, photo-

sensitive means adapted to be activated in response to light decrease produced by indexing means on the container to energize said electrical circuit and stop rotation of the container, means for conveying the container after proper positioning from said positioning station to said printing station, printing means at said printing station to imprint indicia at a predetermined location on the container determined by the position of the indexing means at the positioning station, and reciprocating friction means adapted to frictionally engage the container to roll the container past said printing means.

15. A machine for imprinting indicia at a predetermined location on a cylindrical container, including a positioning station and a printing station, rotatable means at said positioning station for frictionally engaging the container, means for rotating said rotatable means to rotate the container to a predetermined position relative to said printing station, an electrical circuit, means for grounding the container at the positioning station, means including a braking mechanism adapted to grip the container at opposed points thereon and operable upon energization of said electrical circuit to stop rotation of the container in said predetermined position, means adapted to bear against the container as it is being rotated and operable in response to contact with a predetermined bare portion on the container to energize said electrical circuit and stop rotation of the container, means for conveying the container after proper positioning from said positioning station to said printing station, printing means at said printing station to imprint indicia at a predetermined location on the container determined by the position of the bare portion on the container at the positioning station, and reciprocating friction means adapted to frictionally engage the container to roll the container past said printing means.
